Primary Examiner — Susan Moon Lee(74) *Attorney, Agent, or Firm* — Michael J. Feigin, Esq.; Feigin and Fridman LLC(57) **CLAIM**

The ornamental design for a pet bowl, as shown and described.

DESCRIPTION

FIG. 1 shows a top and side perspective view of a pet bowl. FIG. 2 shows a bottom and side perspective view thereof.

FIG. 3 shows a top plan view thereof.

FIG. 4 shows a bottom plan view thereof.

FIG. 5 shows a first side view thereof, the opposite side being a mirror image thereof.

FIG. 6 shows a second side view thereof.

FIG. 7 shows a third side view thereof; and,

FIG. 8 shows a cross section of section line 8-8 of FIG. 3.

1 Claim, 6 Drawing Sheets# US D918,488 S
